Inventor,
Arthur M. Barrett,
officed in the U.S. Patent Office, Atty.

UNITED STATES PATENT OFFICE.

ARTHUR M. BARRETT, OF CHICAGO, ILLINOIS.

BINDER POST.

Application filed June 1, 1926. Serial No. 112,782.

This invention relates to improvements in loose leaf binders, and more particularly to binders capable of being used either singly or in conjunction with telescopic binder 5 covers, and has for its principal object to provide a simple and durable device of the character described, economical in manufacture and capable of being readily attached or detached.

10 In the drawings,

Figure 1 is a perspective view of a pair of binder covers to which my invention has been applied, showing a single locking binding post applied thereto.

15 Figure 2 is an enlarged vertical section taken transversely of the binder, showing the binding post in locked position and with the cover closed thereover.

20 Figure 3 is a sectional view similar to Figure 2 but taken on a line extending longitudinally of the binder, and with an optional form of exterior sleeve which may be used in connection with the post.

25 Figures 4 and 5 are detail plan views of the retaining plate used for securing the upper end of the binding post to a binder cover, such as shown in Figures 1, 2 and 3, and illustrating the manner in which it may be applied with the locking pin extending therethrough.

30 Figure 6 is a plan view of a modified arrangement of binder, in which two detachable binder posts are utilized.

35 Figure 7 is a detail view of a modified form of binding post, drawn to a larger scale than the previous figures, and showing the main parts of the binding post in section.

40 Figure 8 is a detail view of the retaining cap used with the form of binding post shown in Figure 7.

45 Referring now to details shown in the drawings, Figures 1, 2 and 3 show my invention as applied to a binder, indicated generally at 10, and including a top cover 11 and bottom cover 12 having telescopic end portions 11^a and 12^a, respectively, forming the back of the binder. A flange 13 is fixed to the back portion 11^a of the upper 50 cover and extends inwardly, substantially at right angles thereto, and immediately beneath the cover portion 11 when the latter is in closed position, as clearly shown in Figures 1 and 2. This flange is preferably rigid with respect to the back portion 11^a, in the preferred form shown in Figure 2, this

flange being a part of an L-shaped metal piece 14 which is continued downwardly to form the main reinforced part of the back 11^a. The cover 12^a is provided with a similar construction, including an L-shaped metallic piece 15 forming an inward extending flange 16 at right angles to the back 12^a and above the flexibly mounted bottom cover 12.

55 In connection with the oppositely disposed flanges 13 and 16, I provide a plurality of binding posts adapted to extend through the loose leaf filler 17, the leaves of which are suitably punched along their marginal edges and held between the binding posts. In the form shown in Figure 1, two binding posts 18-18 of the ordinary telescoping type, well known to the art, are also provided adjacent the ends of flanges 13 and 16. The construction of these binding posts are well understood and need not be shown in detail.

60 Referring now to the binding posts forming one of the important features of my invention, the binder shown in Figure 1 is provided with a centrally disposed binding post which is shown in greater detail in Figures 2, 3 and 7. This device consists of a tubular base member 20 extending through the bottom strip 16 and having a flanged end 21 engaging the under face of said strip. A cylindrical locking piece 22 extends downwardly through the strip 13 and is provided with a head 23 which engages the upper surface of said strip. This locking piece is of 65 smaller diameter than the bore of the base member 20, and has its lower end split as indicated at 24 in Figure 7. The lower end is also provided on its exterior with serrations 26, adapted to engage with a corresponding serrated portion 25 in the bore of the base member 20 when the split portions are spread outward, as will hereinafter be described. In the form shown, the serrations 26 and 25 are formed by threading their 70 respective members, although it be understood that other forms of serration may be used if desired.

75 A locking pin 30 is mounted by longitudinal movement within the cylindric sleeve 22 and is arranged so that its lower end engages a disposed shoulder 31-31 in said sleeve so as to spread the same into locking engagement when the pin is pushed to its innermost position, as shown in the several 80 figures. Said pin 30 is provided with an enlarged head 31, by which said pin may

be manipulated in locking or unlocking the device.

Two modified forms of devices for retaining the locking cylinder 22 and pin 30 in place, are shown in the figures. In Figures 1, 2 and 3, in which the binding post is used in connection with the binder covers 11 and 12 as described, a strip 35, preferably of metal, is secured adjacent its opposite ends to the upper surface of the binder flange 13. This strip is provided adjacent its center portion with a slot 36 having an enlarged end 37. Said enlarged end portion 37 is of sufficient diameter to permit the main body of the locking pin 30 to extend therethrough, but the reduced slot 36 is of smaller dimensions so that when finally in assembled position, as shown in Figure 3, the strip 35 is placed between head 31 of pin 30 and flange 23 of cylinder 22, so that upward movement of pin 30 will be limited by a shoulder 33 which engages the restricted slot 36 in strip 35. Pin 30 is provided with a restricted portion 34 between shoulder 33 and head 31 so that the device may be readily assembled in the following manner. Before the retaining strip 35 is secured to the upper flange or strip 13, pin 30 is put through the enlarged aperture 37 until the reduced portion 34 of said pin registers with the reduced slot 36 in said strip, as shown in Figure 5. The pin is then shifted laterally so that the reduced portion 34 enters the slot 36 and the pin and strip 35 are then secured to the binder flange 13 as shown in Figure 3.

In the modified form of binding post shown in Figures 7 and 8, the post is especially designed for use without the binder covers, and to this end, a retaining piece 40, similar in function to the strip 35, but in the form of a disc, is secured by crimping the same over the edges of the upper flange 23 of locking sleeve 22, as shown. In other respects, the parts of the binding post are the same.

In connection with all of the forms of binding post described, an auxiliary sleeve 41 may be provided to slip over the outside 50 of the base member 20, but applied from the upper side of the loose leaves, as shown in Figures 3 and 7.

The use and operation of my improved device are now understood. When assembled in the manner hereinabove described, it will be seen that the pin 30 has vertical movement limited by strip 35, or equivalent disc 40, but sufficient to withdraw the lower end to unlock the threaded end of cylinder 22 from the base 20, and permit detachment of the binding post. When the post is to be again locked, the cylindric locking member 22 is inserted in base 20 and may be locked in any vertical position relative thereto by forcing the head 31 down-

wardly, causing the split end of the cylinder 22 to be spread into locking position. It will further be observed in connection with the forms shown in Figures 1, 2 and 3, that the head 31 will be maintained in locking position by the cover 11 when the latter is held in closed position, so that it is impossible to unlock the device unless the cover 11 is open.

Although I have shown and described the particular embodiment of my invention, it will be understood and I do not wish to be limited to the constructions shown and described, but that various changes and modifications may be made without departing from the spirit and scope of my invention.

I claim as my invention:

1. A binding post consisting of two parts detachable by expanding and contracting one of said parts within the other, the expanding part having a flanged portion at one end thereof, an expanding pin operatively disposed within said part and provided with a head projecting above said flanged portion, and an enlarged part spaced vertically below said head, and a securing piece interposed between said flanged portion and said head, said piece having a restricted opening permitting limited vertical movement of said pin.

2. A binding post including two detachably connected telescopic parts, one of said parts having a laterally extending leaf-retaining member, a longitudinally movable pin operative for locking and unlocking said parts having a head disposed above said retaining member and an enlarged part spaced vertically below said head, and means for securing and limiting the movement of said locking member relative to the part on which it is carried, comprising a piece having a slot of varying width whereby the enlarged part of said pin may pass only through the larger part of said slot, said piece being fixed relative to said retaining flange in position with said pin passing through a smaller part of the slot.

3. A binding post consisting of two parts detachable by expanding and contracting one of said parts within the other, the expanding part having a flanged leaf retaining portion, an expanding pin operatively disposed within said part and provided with a head projecting above said flanged portion, and a securing piece secured over the edge of said flanged portion and interposed between said flanged portion and said head, said piece having a restricted opening permitting limited vertical movement of said pin.

4. A binding post including two detachably connected telescopic parts, one of said parts having a laterally extending leaf-retaining member, a longitudinally movable pin operative for locking and unlocking said parts having a head disposed above said re-

- taining member and an enlarged part spaced vertically below said head, and means for securing and limiting the movement of said locking member relative to the part on which it is carried, comprising a piece having a slot of varying width whereby the enlarged part of said pin may pass only through the larger part of said slot, said piece being secured over the edge of said retaining flange in position with said pin passing through a smaller part of the slot.
5. In a loose leaf binder, a pair of oppositely disposed retaining members, a binding post including two telescoping parts each connected with one of said retaining members, means for detachably connecting said telescoping parts including a longitudinally movable locking member extending through one of said retaining members and its respective telescopic part, and having a head extending above said retaining member, and means for securing and limiting the movement of said locking member relative to said retaining member, comprising a piece fixed 20 relative to said retaining member and interposed between the same and said head, said piece having a restricted opening permitting limited vertical movement of said locking member.
- 25 6. In a binder, a pair of oppositely dis-
- posed retaining members, a binding post consisting of two telescoping parts each connected with one of said retaining members, means for detachably connecting said telescoping parts including a longitudinally 35 movable member extending through one of said retaining members, and a cover flexibly connected to, and adapted to fold over said last named retaining member and retain said movable member in locked position 40 when said cover is in closed position.
7. In a loose-leaf binder, a pair of L-shaped pieces adapted to fit in telescoping relation to form the back of the binder, and with inwardly extending portions adapted 45 to form retaining members for opposite sides of the leaves to be bound, a telescoping binding post having two parts each connected to one of said retaining members, means for detachably connecting said parts including a longitudinally movable member extending through one of said retaining members, and a cover flexibly connected to the last-named retaining member and foldable over the latter to maintain said longitudinally movable 50 member in locked position when said cover is closed.
- Signed at Chicago, Ill., this 27th day of May, 1926.
- ARTHUR M. BARRETT.
